UNITED STATES PATENT OFFICE.

THOMAS CARROLL, OF DAYTON, OHIO, ASSIGNOR TO THE NATIONAL CASH REGISTER COMPANY, OF DAYTON, OHIO, A CORPORATION OF OHIO. (INCORPORATED IN 1906.)

CASH-REGISTER.

1,092,975.

Specification of Letters Patent. Patented Apr. 14, 1914.

Application filed February 5, 1907. Serial No. 355,924.

To all whom it may concern:

Be it known that I, THOMAS CARROLL, a citizen of the United States, residing at Dayton, in the county of Montgomery and State of Ohio, have invented certain new and useful Improvements in Cash-Registers, of which I declare the following to be a full, clear, and exact description.

This invention relates to cash registers and has among its objects to provide a positively acting registering mechanism having practically no springs employed to perform any parts of the operation.

A further object is to provide a machine having setting levers for determining the entry on the registering mechanism, the levers being returned independently to normal position at each operation of the machine and having no control over the counter during such return.

Another object is to provide a registering device which is locked at all times except when under the direct positive control of the operating and transfer mechanisms.

Other objects are to provide a transfer mechanism normally locked against movement and unlocked only when the transfer is to take place, and an improved resetting device for the registering mechanism.

With these and incidental objects in view the invention consists in certain novel features of construction and combination of parts, the essential elements of which are set forth in appended claims and a preferred form of embodiment of which is hereinafter set forth with reference to the drawings which accompany and form part of this specification.

Of said drawings: Figure 1 is a transverse vertical section through the machine showing the actuating and transfer devices for the registering mechanism. Fig. 1^a is a detail showing the lock for the transfer pawls. Fig. 1^b is a detail showing the auxiliary device for resetting the setting lever. Fig. 1^c shows parts of Fig. 1 enlarged. Fig. 1^d is a detail view of the transfer controlling arm 123. Fig. 1^e is a detail view of the transfer bar 126. Fig. 2 is a transverse vertical section through another part of the machine showing the mechanism for preventing operation of the counter. Fig. 2^a is a detail of parts shown in Fig. 2 for resetting the transfer arms. Fig. 3 is a transverse vertical section near one end of the machine looking

in an opposite direction from Figs. 1 and 2 showing the actuating devices for the register and operating devices for certain locking mechanisms. Fig. 4 is a detail showing means for releasing the register locking pawls. Fig. 5 is a perspective of one of the setting levers. Fig. 6 is a front elevation of the registering mechanism.

Machines of the general type shown in this case are disclosed in prior applications Nos. 236,285, filed Dec. 10, 1904 and 270,786, filed July 22, 1905.

In general it may be said that a series of setting levers are provided serving to differentially position controlling racks and pinions geared thereto as well as positioning an indicator operating device. The register is normally disconnected from the actuating gearing but is arranged to be thrown into connection therewith during the return of said gearing to its normal position, whereas the setting levers are disconnected from the said gearing and are independently returned to normal position thereby preventing a possible manipulation of the machine. During the operation of the counter as stated the setting levers are held rigidly in their adjusted position and are not unlocked until the operation of the counter has been completely finished. Pawl devices for normally locking the counter are provided and these are not released until the actuating gears have been connected to the counter, this in connection with a positive transfer providing a continuous lock for the registering mechanism at all times. By these important provisions the counter is prevented from manipulation even if the cabinet is removed from the machine. It is impossible to turn the counter wheels even if manual access may be had thereto except through the ordinary operating devices of the machine or the zero setting mechanism, the operation of either of which serves to leave its own traces in the machine. Indicating and printing mechanisms are also provided, the operating devices for the indicator being the same as those shown in the prior applications.

It will be understood that any desired number of banks of denominational elements may be provided and I have therefore shown only one bank it being evident that additional banks would be precisely similar thereto. A setting lever 19 is provided as

shown on Fig. 1 this lever being shown separately on Fig. 5. All the levers are journaled loosely on the supporting rod 26 and are provided with a cam slot 27, segment gears 28 and 29 and a ratchet 30 besides an abutting segment 31. The segment gear 29 meshes with a segment gear 32 fastened rigidly to a segment lever 33 pivoted on shaft 34 and carrying at its upper end a rack 35. The setting lever 19 is shown in Fig. 1 in normal position and when the operator inserts a finger in one of the ten depressions 36 shown on Fig. 5 and depresses the lever until the finger strikes a projecting part 15 of the cabinet, controlling segment 33 will evidently be caused to assume differential position in accordance with the movement of said lever. The registering mechanism comprises a series of counter wheels 41 shown in Figs. 1 and 6 journaled on a rod 42 and provided with pinions 43 for actuating the same. Almost directly below the register shaft 42 is a supporting shaft 44 on which are mounted sets of gears there being provided three gears for each register wheel 41 as shown in Fig. 6. The rack 35 of the segment lever 33 is adapted to gear with right hand pinions 46 of each of the sets, the left hand pinions of each of the sets being 20 geared to the register pinions 43. The intermediate gears 48 of the sets are adapted to be sometimes connected to the gears 46 and at other times connected to the gears 47. Directly in the rear of the shaft 44 is a rod 51 supported as shown in Fig. 2 by frame arms 52 journaled on shaft 53 one of the arms 52 being provided with a rearward extension 54 having an antifriction roller 55 moving in a cam groove of a disk 56 rigidly 25 mounted on a main operating shaft 57^a of the machine. The shape of the groove of the disk 56 is such that the pinions 57 mounted on rod 51 are normally in gear with the actuating gears forward of them, and adapted to connect the gears 46 to the gear 48 as shown in Fig. 6. From this description it will be clear that any of the setting segment levers 19 will cause a rotation of its gear 46 and this through pinion 57 will cause an equal rotation of gear 48 connected thereto. A second set of pinions 61 are provided each supported by an arm 62 rigidly mounted on shaft 63, this shaft being oscillated at each operation of the machine by a lever 64 actuated by an antifriction roller 65 moving in a cam groove of a disk 66 also rigidly mounted on shaft 57^a. The shape of the cam groove is such that while pinions 61 are normally out of mesh 30 with the gears 48, these are nevertheless thrown into mesh for a part of each rotation of the shaft 57^a, such pinions 61 serving to connect the gears 48 with the operating gears 47 for the counter wheel. When pinions 61 have been so raised as to

connect the gears 47 and 48, the gears 48 are returned to normal position as hereafter described and this return will clearly serve to add an equal amount on the register wheels. As the pinions 57 are at this time out of mesh with the gears 46 and 48 no reverse motion of gear 46 is given and in fact the segment lever 19 is at this time locked.

To cause the reverse motion of gear 48 to advance the register wheel mechanism shown in Figs. 1 and 3 is employed. Each of the gears 48 is provided with a pin 71 normally above a pin 72 projecting from the supporting shaft 44 for the gears. When the segment levers 19 are actuated the pins 71 will move the projections 72, thereby rotating the shaft 44 to an amount equal to the greatest movement of any of the gears 48. On the end of shaft 44 is a pinion 73 shown in Fig. 3 with which meshes a segment gear 74 journaled on a pin 75 and provided with a rearwardly extending arm 76 provided near its rear end with an antifriction roller 77 adapted to be engaged by a cam 78 on operating shaft 57^a. The cam 78 is shown in normal position in Fig. 3 and it will be seen that the rocking of shaft 44 will cause the antifriction roller 77 to pass within the circle of rotation of the cam 78. When the shaft 57^a is rotated the cam 78 will sooner or later strike the antifriction roller 77 and positively return the segment gear 74 to the position of the figure thus reversely moving shaft 44 through whatever extent it had been moved by the segment levers 19. During this part of the operation as stated, pinions 61 are in mesh with gears 47 and 48 so that the rotation of shaft 44 returning it to normal position serves to actuate the counter.

As gears 48 reach home position, pins 481 carried by each of said gears, strike projections 482 on arms 62. This serves to positively stop the gears 48 and prevent over-throw of the register wheels 43.

A second operating shaft 81 is provided in the machine, the two shafts 57^a and 81 being geared together by gears 81^a and 81^b and the operating handle 81^c being mounted on the shaft 57^a in such manner that one complete rotation will be given at each operation of the machine to both said operating shafts. The shaft 81 as shown in Fig. 2 is provided with a cam 83 engaging an antifriction roller 84 on a forwardly extending arm 85. This arm is bifurcated at its rear end to straddle the shaft 81 and at its forward end is pivoted to a frame bar 86 mounted on rod 34 and supporting the rod 87 directly in the rear of segments 33. When shaft 81 is rotated the cam 83 will finally force the arm 85 forwardly through contact with roller 84 and thereby will cause bar 87 to abut the segments 33 and positively return them to normal position. It will be

noted that the position of the cam 83 is such that the registering has all taken place before the segments 33 are returned. To assist in the final movement of return of the segments a shaft 91 (Fig. 1) is provided with a depending arm 92 shown in normal position in full lines and adapted to engage a pin 93 mounted on the segment 33, it being understood that the arm 92 and a pin 93 are provided for each segment 33. The shaft 91 as shown in Fig. 1^b has rigidly mounted thereon an arm 94 operated by a link bar 95 straddling the shaft 57^a and operated through an antifriction roller 96 on said bar 95 by a cam groove in a disk 97 on said shaft. It will be seen from the shape of the cam groove that the shaft 91 is rocked during the return of the setting segments 33 causing the arms 92 to finally press the pins 93 on said segments thereby assisting and making more sure the return of the segments to normal position and is then retracted to the full line position of Fig. 1 so that the segments 33 may again be manually operated.

A positively acting transfer mechanism has been devised and may next be described. Each register wheel (Figs. 1 and 1^c) except that of highest order is provided with a cam projection 101 serving to actuate a transfer trip pawl. These trip pawls in the present case comprise bell crank levers 102 journaled loosely on a rod 103 and provided with a projection as usual in the path of cams 101. The forward ends of the trip pawls 102 are provided with two notches 104 and 105 in either of which a locking bell crank 106 is adapted to engage. The bell cranks are pivoted loosely on a rod 107 and their lower extensions are provided with lateral pins 108 adapted to engage one of two notches 109 in a disk carried by the counter operating gear 47. The pawls 106 through their supporting rod 107 are carried on one arm 112 of bell crank levers 112 loose on shaft 44 and are operated by links 113 carrying antifriction rollers 114 moving in cam grooves of disks 115 rigidly mounted on shaft 57^a. The bellcrank locking arms 106 are mounted on a floating pivot for the purpose of releasing the trip pawls 102 after the transfers are added in to allow the trip pawls to be rotated to normal position. When the pawls are tripped by cams 101 notches 109 allow movement of pins 108 but the notches 109 have moved past before pawls 102 are restored. In this case the rocking of arm 112 withdraws arms 106 so as to allow resetting of trip pawl 102. Each of the trip pawls 102 is provided with a cam slot 121 in which moves a pin 122 on a transfer controlling arm 123, the pin 122 being supported from the vertical extension 124 of said arm. These arms 123 are journaled on shaft 125 being cut away as shown in Fig. 1 to allow

forward movement. The slots 121 are cut concentric with the shaft 125. The transfer operating device comprises a bar also journaled on shaft 125 to allow forward and rearward movement, this bar being numbered 126 and being provided at its rear end with a vertical slot moving past a pin 128 on a lever 129 mounted on shaft 130. This transfer bar 126 is provided on its upper side with a lug 131 and on its lower side with a lug 132 and is shaped at its forward end to provide two transfer teeth 133 adapted to engage with a register pinion 43. Connected by a longitudinal slot and pin 134 to the arm 123 is a bell crank lever 135 carried by shaft 125 and provided at its lower end with an antifriction roller 136 riding in the cam groove in a disk 137 mounted on the shaft 57^a. The shaft 125 is provided with a series of projections 141 in front of and adapted to engage pins 142 on the arms 123. This shaft is rocked as shown in Fig. 2^a by an arm 144 connected rigidly thereto and to a link 145 bearing an antifriction roller 146 riding in a cam groove of a disk 147 rigidly carried by shaft 57^a, the shape of the groove being such that as soon as the shaft 57^a starts to rotate, the shaft 125 is rocked forwardly and held there until nearly the end of the operation when it is rocked rearward again and remains at the rearward extremity of its movement until a succeeding operation. This rocking of the shaft 125 serves to return to normal position, the transfer controlling arms 123 and through the pins 122 and slots 121, restores the trip pawls 102.

The operation of this transfer mechanism is as follows: When any of the counter pinions 43 pass through the zero position the cams 101 strike the trip projection of trip pawls 102 rocking the pawl in a counter clockwise direction (Fig. 1^c) around its pivot on shaft 103. The trip pawls 102 are normally locked by bell cranks 106 but when the cam 101 approaches the tripping position the notch 109 registers with the pin 108 of the locking pawls 106 to allow the trip pawls 102 to move. The rocking of the trip pawls 102 serve to move the arms 123 bodily forward through the connection at pin 122 thereby carrying the notch 161 of the arms some distance forward. The shaft 130 is rocked at each operation by arm 171 bearing antifriction roller 172 moving in cam groove of disk 173 carried by shaft 57^a and this rocking serves to move forward the arms 129 and therefore carry the transfer pawls 126 forward so that the teeth 133 mesh with the next higher counter pinion 43. The flanges 131 of the transfer pawls 126 are of course moved forwardly with the pawl but not far enough to pass over the depressions 161 of the arms 123. When the transfer pawls have so moved forward they are rocked

around their pivot on shaft 125, by the arms 135 to turn in the transfers. When the teeth 133 have finished their upward movement the transfer pawls 126 are rocked backward by the cam groove in disk 173 and are then rocked downwardly by the return movement of arms 123 through the medium of flange 132 on the transfer pawl. When the arms 123 are rocked around their pivots the pins 122 carried thereby will evidently move in the slots 121 of the trip pawls without any movement thereof. If no transfer is to take place the transfer pawls 126 are nevertheless moved forwardly by the rocking of shaft 130, and flanges 131 are then carried over depressions 161 so that when the arms 123 are rocked from the cam disks 137, the depressions 161 will merely pass up around the flanges 131 of the transfer pawls without raising them. To prevent accidental frictional raising of the pawls 126 the trip pawls 102 are each provided with a lateral pin 181 under which the edge of the transfer pawl is adapted to move when the pawls 126 are thrown forwardly. Of course if the trip pawl is thrown forwardly the forward movement of the transfer pawl is not great enough to bring the edge thereof under the pin 181 but if the trip pawl remains in normal position the transfer pawl will move far enough forward to engage its upper edge under the pin 181 and thereby prevent it from being accidentally rotated around its pivot 125. This transfer mechanism has been described partly in singular and partly in plural but it will of course be understood that a set of transfer mechanisms is provided for each denomination of the counter wheels and the cams in disks 137 are so arranged as to successively operate the transfers. With the mechanism shown it is necessary to operate from the lowest to the highest order in succession and furthermore the disk 173 must rock the arms 129 before the disks 137 rock the arms 135. For example with a six denomination counter it would be necessary to provide six successively operated cams during one rotation of shaft 57^a, but this is not difficult for the reason that the direct operation of the counter takes place during the very first part of the rotation of the shaft and for the further reason that the entire transfer mechanism is positive and therefore need not wait for springs to force an element to desired position. This transfer is very quick and at the same time there is no possibility of turning the handle so rapidly that the transfers miss as is sometimes the case when trip pawls are spring controlled.

The counter wheels are locked at all parts of the operation except when under the control of the operating or the transfer devices and to accomplish this a series of locking pawls 201 are provided which as shown in

Fig. 1 normally engage the actuating gears 47. These pawls are rigidly mounted on shaft 53 which also carries a rigid arm 203 as shown in Fig. 4. The arm has spaced projections 205 and 206 and adjacent to this arm 203 is a second arm 207 provided with a flange 208, lying between the projections 205 and 206 and normally forced against the projection 206 by the spring 209 between the flange and the projection 205. The arm 207 has a slot and pin connection 210 with a lever 211 connected at the top to a sliding bar 212 and provided at the bottom with an antifriction roller 213 riding in a cam groove 214 of a disk 215 rigidly carried on shaft 57^a. It will be seen that as shaft 57^a rotates the antifriction roller 213 will be forced to the rear thereby rocking the arm 207 and through flange 208 compressing the spring 209, which compression serves to rock the shaft 53 and withdraw the locking pawls 201 from the gear wheels 47. At the end of the operation the pawls are forced back to locking position by the return of the antifriction roller 213 under the influence of cam groove 214.

With the mechanism as thus far described the spring 209 has no function as it would be possible to positively force the locking pawls 201 in both directions but the machine is designed to provide a so-called throwout counter and in case the operation of the register is prevented it is not desired to release the locking pawls. One of the segments 19 will be used to control the entry of transactions in the machine and will be provided as shown on Fig. 2 with a rearwardly extending arm 221 carrying an upward projection 222. The arm 64 which serves to rock the pinion 61 into mesh with the gears 47 and 48 is operated by a link 223 shown on Fig. 2 and to prevent the operation of the counter it is clearly only necessary to disengage link 223 from the arm 64 by raising it to the position shown in dotted lines. This will be accomplished when the special transaction lever is set to enter the transaction of some desired class, when the projection 222 will engage a pin 224 on the link 223 rocking the said link enough to destroy the connection between it and the arm 64. The rearward end 225 of arm 221 passes in front of a depending projection 226 fast to shaft 53 which carries the locking pawls 201. When the machine is set for a special transaction and the pawls 201 are locked as shown in Fig. 2 the operation of cam disk 215 in Fig. 4 will merely serve to tension the spring 209 without releasing the locking pawls.

The segment levers 19 are desirably locked in adjusted position during the operation of the register mechanism and to accomplish this the locking and alining arms 221 are provided as shown on Fig. 1 journaled loosely on shaft 232 and provided with

plates 233 riding loosely in a slot cut in said shaft. A shaft 234 carries an angular locking bar which is arranged to be rotated by an arm 235 fast thereon connected to a link 236 bearing an antifriction roller 237 which rides in a groove 238 of a cam disk 239 fast on shaft 81. From the shape of the cam groove it will be seen that the locking piece on shaft 234 is rocked rearwardly to force the arms 231 positively into the notches 31 which move with the segments 19. After the locking piece has been returned to normal position it is desirable to slightly withdraw the locking arms 231 to avoid too much friction during the return of segments 19 and for this purpose the plates 233 are provided and an arm 241 mounted rigidly on shaft 232 and operated by a cam 242 on shaft 81 serves to rock the said arms 231 slightly forward to allow a return of the segments 19. To prevent opposite motion of segments 19 during their return, arms 243 are adapted to engage a ratchet 30 mounted thereon. This device may be considered as a full stroke device, but is more particularly a device to prevent intentional abuse of the machine by returning the members 19 and connected parts to normal position ahead of the rod 87 and then quickly carrying them back into contact with said rod, thereby bending or straining the mechanism so as to make it add or indicate incorrectly. These arms are journaled on shaft 244 being connected thereto through plates 245 engaging a slot in said shaft, the shaft being provided with an arm 246 (Fig. 3) adapted to be released by a bell crank comprising arms 247 and 248 the rear end of the arm 248 being normally engaged by an antifriction roller 249 carried on cam 242. The lower end of the arm 243 has bent flanges 250 and provided with holes through which pass plungers 251 surrounded by springs compressing against the lower plates 250 and an enlarged portion of the plunger. Thus it will be seen the upper enlarged ends of the plungers abut the arms 231 thereby forcing the arms 231 lightly into the segment notches 31. When the mechanism is in normal position the parts are as shown in Fig. 1, and the segments 19 may be rotated around their supporting shafts 26 causing the notches 31 to move in succession past the arms 231 thereby tensioning springs of the plungers 251 and releasing them again rapidly. The arms 243 cannot at this time rock around their shaft as their plates 245 are against the side of the shaft 244. When the operating handle turns the shaft 81 the shaft 234 is rocked throwing the angular locking plate against the arms 231 and positively locking the segment levers 19 in adjusted position. At this time the shaft 232 is slightly rocked so that the arms 231 may be moved as stated. After the counter has been completely op-

erated the shaft 234 is reversely rocked thereby releasing the arms 231, and as by this time roller 249 has passed from over the bellcrank arm 248 the springs of the plungers 251 may force the arms 243 rearwardly causing them to engage ratchets 30 thereby preventing opposite movement of the segment levers 19 during their return to normal position. The shaft 244 has meanwhile been rocked by arm 246 to allow the movement of the arms 243 they being normally as shown in position such that plates 245 thereof are against one edge of the slot of shaft 244. The roller 249 finally operates the bell cranks 248 serving to withdraw the arms 243 from the ratchets 30 and the mechanism then again assumes its normal position.

Indicating mechanism is provided similar to that shown in the prior application and only a general description thereof will be given. A cylinder indicator 301 is provided for each segment lever having connected thereto pinions 302 meshing with segment gears 303 driven by arms 304 which arms are connected through links 305 to levers 306 provided at their forward ends with antifriction rollers 307 moving in the cam slots 27 of the segment levers 19. Near their center points the levers 306 are pinned to vertical bars 308 having slots 309 surrounding the shaft 81 and being held to move in a frame piece 310. The vertical bars 308 are provided upon opposite sides thereof with antifriction rollers 311 and 312 adapted to be engaged respectively by cams 313 and 314. When the segment levers 19 are oscillated the cam grooves 27 serve to rock levers 306 around their pivots 316 as at this time the indicators are locked as is usual in cash registers. When the operating handle starts the segment levers 19 are locked as before stated and the cams 313 and 314 return the vertical arms 308 to their normal position through rollers 311 and 312, the indicators having meanwhile been unlocked. The indicators are then again locked and segments 19 finally returned to normal position raising the levers 306 depending on the position of their pivots 316.

The segments 19 are as stated provided with segment gears 28 meshing with pinions 327 on the ends of a series of nested sleeves 328. The outer ends of these nested sleeves carry printing wheels as is common in the art.

To reset the counter mechanism each counter wheel is provided with a beveled projection 361 adapted to be engaged by a corresponding beveled projection 362 on the counter shaft 42. The opposite ends of the shaft are provided with pins 363 and 364, the pin 363 being normally at the apex of a bent camming plate 365 and pin 364 being normally at the depressed center of a

second camming plate 366. When the shaft 42 is rotated by the knob 367 the plate 366 will force the said shaft laterally carrying the beveled projection 362 into the plane of movement of the wheel pins 361 so that at sometime during the rotation of the shaft the wheel pins 361 will be engaged by the beveled pins 362 and move backward to the position of Fig. 6. When this position is nearly reached the pin 363 will ride up the bent portion of plate 365 thereby reversely moving the shaft 42 to its normal position. Inasmuch as the wheels are set backwardly the transfer trip pawls are not tripped and it is only necessary to withdraw the counter locking pawls 201. This is the reason for the floating pivot shown in Fig. 4. Shaft 42 is provided with a disk 371 having a cam groove 372 in which rides a pin 373 on the sliding plate 212. It will be clear that when the shaft 42 is rotated to reset the counter, the plate 212 will be sid rearwardly thereby rocking the arm 207 as was the case when the shaft 57^a was rotated and securing precisely the same withdrawal of the locking pawls 201.

It is thought that the operation of the mechanism will be clear from the description given.

30 The machine can be operated very rapidly as the mechanism is all positively actuated and danger of over-running thereby prevented.

The register is at all times under control 35 of a locking device except when being positively operated and the locking device is not released until the operating mechanism is ready to actuate the register.

While the form of mechanism here shown 40 and described is admirably adapted to fulfil the objects primarily stated, it is to be understood that it is not intended to confine the invention to the one form of embodiment herein described, for it is susceptible of embodiment in various forms all coming within the scope of the claims which follow.

What is claimed is as follows:

1. In a registering mechanism, the combination with a computing device, operating means therefor, a controlling device for said operating means, means for adjusting said controlling device normally connected thereto, and separate mechanisms for disconnecting the controlling device from the adjusting means and for connecting it with the operating means.

2. In a registering mechanism, the combination with a computing device, operating 60 means therefor, a controlling device for said operating means, means for adjusting said controlling device normally connected thereto, and mechanism for disconnecting the controlling device from the adjusting means and connecting it with the operating means

and thereafter independently returning the controlling device and the adjusting means to normal position.

3. In a registering mechanism, the combination with a computing device, and an operating gear for same, of additional gears beside said operating gear, manipulative devices for adjusting said additional gears differentially, means for disconnecting said additional gears and connecting said operating gear to one of the same, means for restoring the gear connected to the operating gear to normal position, thereby actuating said computing device and means for thereafter independently restoring said manipulative devices also to normal position. 70

4. In a registering mechanism, the combination with a computing device and an operating device connected to same, controlling and positioning devices for same, separate means for connecting said controlling and positioning devices and said operating and controlling devices, for movement in opposite directions, and means for successively operating said connecting means. 85

5. In a registering mechanism, the combination with a computing device, of operating mechanism for same, controlling and positioning devices for said operating mechanism, separate means for successively connecting said controlling and positioning devices and said operating and controlling devices for movement in reverse directions, manipulative devices for moving said positioning devices in one direction and means for moving said controlling devices in the opposite direction to operate said computing device. 90

6. In a registering mechanism, the combination with a computing device, operating means therefor, a controlling device for said operating means, means for adjusting said controlling device normally connected thereto, and mechanism for disconnecting the controlling device from the adjusting means and connecting it with the operating means and thereafter independently returning the controlling device and the adjusting means to normal position, by which movement of the controlling device the computing device is operated. 105

7. In a registering mechanism, the combination with a computing device, of means for controlling same, differentially movable device for positioning said controlling means, means for restoring said controlling means to normal position and thereby operating said computing device, and means for thereafter restoring said differentially movable devices also to normal position. 120

8. In a registering mechanism, the combination with a computing device and operating and controlling means for same, a shaft for supporting said operating and controlling means, means for positioning differ- 130

entially said controlling means and shaft, and means for restoring said shaft to actuate said computing device.

9. In a registering mechanism, the combination with a computing device of operating and controlling gears for same, a shaft supporting said gears, means for differentially positioning said controlling gear and thereby setting said shaft, means for resetting said shaft to normal position to restore said controlling gear, and means for connecting said operating and controlling gears during said resetting of said shaft.

10. In a registering mechanism, the combination with a computing device and an operating gear therefor, of a shaft supporting said gear, means for rotating said shaft in one direction, manipulative devices operating said means, a cam for resetting said shaft to normal position, and means for connecting said operating gear to said shaft during said reverse movement.

11. In a registering mechanism, the combination with a computing device, of operating, controlling and positioning gears for said device, manipulative devices for adjusting said positioning gear, a pinion connecting said positioning and controlling gear during operation of said manipulative devices, means for restoring said controlling gears to normal position, and a pinion for connecting said operating and controlling gears for the reverse movement, thereby actuating said computing device.

12. In a registering mechanism, the combination with a computing device and operating devices for same, of differentially movable manipulative devices controlling the operating devices, means for actuating the operating devices, means for locking the manipulative devices during such actuation, and means for separately resetting the manipulative devices to normal position.

13. In a registering mechanism, the combination with a computing device, of controlling devices therefor, differentially movable manipulative devices for positively adjusting the controlling devices, means for restoring the controlling devices to normal position to actuate the computing devices, means for preventing movement of said manipulative devices during said restoration, and means for thereafter positively restoring said manipulative devices to normal position.

14. In a registering mechanism, the combination with a computing device, of manipulative differentially movable devices for determining the entry on said devices, means for positively restoring said manipulative devices to normal position, and a pawl thrown into connection with said manipulative devices during such restoration and preventing backward movement of same.

15. In a registering mechanism, the com-

bination with a registering mechanism and pawls normally locking same, of an operating mechanism, a turn to zero device for said registering mechanism, and means for withdrawing said locking pawls by actuation of either said operating mechanism or said turn to zero device.

16. In a registering mechanism, the combination with a registering mechanism, and operating and transfer devices for same both said operating and transfer devices acting positively, of pawls for locking said registering mechanism, with means for withdrawing said pawls, the construction being such as to time the operation of said operating devices, transfer devices and locking pawls so that the registering mechanism is under control of one of said instrumentalities at all periods of operation.

17. In a registering mechanism, the combination with a registering mechanism and transfer and operating devices for same, of pawl devices normally locking said mechanism and cams for connecting and disconnecting said operating, transfer and pawl devices to said mechanism, the cams being timed to bring one of said devices into operation before another is disconnected.

18. In a registering mechanism, the combination with an operating mechanism, of a register actuated thereby, a manipulative element for controlling the amount to be entered on said register by differential movements of said element, means for positively returning the manipulative element to normal position, and a pawl thrown into connection with said element at each operation preventing movement of said element in one direction.

19. In a registering mechanism, the combination with a registering mechanism, of a manipulative element for determining the amount entered on said register, means for positively returning said element to normal position, and an auxiliary device for assisting the final increment of movement for the purpose specified.

20. In a registering mechanism, the combination with registering elements, of transfer racks, one for each element, normally withdrawn from said elements, levers tripped by said registering elements when a transfer is necessary, means for simultaneously meshing the transfer racks with the registering elements, and means for successively actuating those of said racks whose levers have been tripped.

21. In a registering mechanism, the combination with registering elements, of transfer racks for said elements normally withdrawn therefrom, transfer trip pawls moved by said registering elements, actuators for said transfer racks moved by said trip pawls, means for simultaneously engaging all said transfer racks with said registering

elements, and means for successively actuating the actuators for said transfer racks.

22. In a registering mechanism, the combination with registering elements, of transfer racks for said elements normally separated therefrom, transfer trip pawls moved by said registering elements, actuators for said transfer racks controlled by said trip pawls, means for bringing said transfer racks and registering elements into connection, and means for operating said actuators.

23. In a registering mechanism, the combination with registering elements having driving gears, of transfer racks for actuating said gears but normally disconnected therefrom, bell crank transfer trip pawls operated by said driving gears, actuating slides for said transfer racks with means for rocking them, devices connecting said trip pawls to said actuators, means for sliding said transfer racks into mesh with said driving gears, and devices whereby the unoperated trip pawls lock the transfer racks after the same have been connected to the driving gears.

24. In a registering mechanism the combination with registering elements and driving means therefor, of locking pawls for said elements, and a "throw out" device for preventing actuation of said driving means, said "throw out" device being positioned and constructed to latch said locking pawls when actuation of the driving means is prevented.

25. In a registering mechanism, the combination with a computing device, of operating means therefor, a controlling device for said operating means, means for adjusting said controlling device and separate means for connecting the adjusting means and controlling device and the latter with the operating means.

26. In a registering mechanism, the combination with a computing device, of operating means therefor, a controlling device for said operating means, means for adjusting said controlling device, and a plurality of pinions for connecting the adjusting means and the controlling device and the latter with the operating means.

27. In a registering mechanism, the combination with a computing device, of operating means therefor, a controlling device for said operating means, means for adjusting said controlling device, a plurality of pinions for connecting the adjusting means and the controlling device and the latter with the operating means, and a plurality of cams, one of which disengages the pinion connecting the adjusting means and the controlling device and the other of which connects the remaining pinion with the controlling device and the operating means.

28. In a registering mechanism, the combination with a plurality of registering ele-

ments and operating and turn to zero devices therefor, of means for normally locking said elements, and resilient means controlled by either the operating or turn to zero devices for unlocking the movable elements.

29. In a machine of the class described, the combination with a registering mechanism comprising a plurality of movable elements, and operating mechanism therefor, of transfer devices normally out of engagement with the movable elements, actuators for said devices, means for bringing all of said elements and devices in engagement, upon each operation of the machine, and means controlled by the elements for determining the devices to be operated by the actuators to effect a transfer.

30. In a machine of the class described, the combination with a registering mechanism comprising a plurality of movable elements, and operating mechanism therefor, of transfer devices normally out of engagement with the movable elements, actuators for said devices, means for bringing all of said elements and devices in engagement upon each operation of the machine, means controlled by the elements for determining the devices to be operated by the actuators to effect a transfer, and means for locking the unoperated transfer devices.

31. In a registering mechanism, the combination with a plurality of registering elements, of operating and transferring mechanisms therefor, means positively locking said registering elements when out of the control of either of said mechanisms, and means for simultaneously withdrawing all of said locking means when said elements are under the control of said mechanisms.

32. In a registering mechanism, the combination with a plurality of registering elements, of operating and transferring mechanisms therefor, a shaft and a plurality of pawls fast thereon for positively and simultaneously locking said registering elements when out of the control of either of said mechanisms, and means for rocking said shaft to simultaneously withdraw the pawl from locking position when said elements are under the control of said mechanisms.

33. In a registering mechanism, the combination with a plurality of registering elements, of operating mechanism therefor, means positively and simultaneously locking all of said registering elements when out of the control of the operating mechanism, and means for simultaneously withdrawing all of said locking means when said elements are under the control of said mechanism.

34. In a registering mechanism, the combination with a plurality of registering elements, of operating mechanism therefor, a shaft, and a plurality of pawls fast thereon for positively and simultaneously locking all

of said registering elements when out of the control of the operating mechanism, and means for rocking said shaft to withdraw the pawls from locking position when said elements are under the control of said mechanism.

35. In a registering mechanism, the combination with a plurality of registering elements, of operating and transferring mechanisms therefor, a shaft, and a plurality of pawls fast thereon for positively locking said mechanisms, a spring for rocking said shaft to simultaneously unlock all of said elements, and means for tensioning the spring to rock the shaft when said elements are under the control of said mechanisms.

36. In a registering mechanism, the combination with a plurality of movable elements, of operating, transferring and resetting mechanisms therefor, means positively locking said elements when out of the control of any of said mechanisms, and means for withdrawing simultaneously all of said locking means when said elements are under the control of any of said mechanisms.

37. In a registering mechanism, the combination with a plurality of movable elements, of operating, transferring and resetting mechanisms therefor, a shaft, and a plurality of pawls fast thereon each for positively locking a corresponding one of said elements when the elements are out of the control of any of said mechanisms, and means for rocking said shaft to withdraw the pawls from locking position to simultaneously unlock the members when said elements are under the control of any of said mechanisms.

38. In a registering mechanism, the combination with a plurality of movable elements, of operating, transferring and resetting mechanisms therefor, a shaft, and a plurality of pawls fast thereon for positively locking said elements when out of the control of any of said mechanisms, a spring for rocking said shaft to withdraw the pawls from locking position, and a cam for tensioning the spring to rock the shaft when said elements are under the control of any of said mechanisms.

39. In a machine of the class described, the combination with an indicating mechanism constructed to indicate all classes of transactions entered in the machine, of a registering mechanism comprising a plurality of movable elements and constructed to register only certain classes of transactions, an operating mechanism for said registering mechanism normally out of operative relation therewith, means preventing movement of the elements of the registering mechanism while out of operative relation with the operating mechanism, means for establishing an operative relation between the registering and the operating mechanisms

and rendering the preventing means inoperative, and means for holding the preventing means and elements of the registering mechanism in operative relation when it is desired to indicate a transaction that is not to be registered.

40. In a registering mechanism, the combination with a plurality of movable elements, of operating devices therefor normally out of operative relation therewith, means normally preventing movement of said elements, means for establishing an operative relation between the elements and operating devices and rendering the preventing means inoperative, and means operable at will for preventing the establishing of such operative relation between the elements and operating devices, with connections whereby said means also controls the disengagement of the preventing means and the movable elements.

41. In a registering mechanism, the combination with a plurality of movable elements, of devices differentially adjustable from normal position, means for connecting the elements and devices while the latter are in their adjusted positions and then returning the devices to normal position to actuate the elements of the registering mechanism, means positively preventing movement of said elements while disconnected from the actuating devices, with connections whereby said means is rendered inoperative when the actuating devices and elements are connected, and means operable at will for preventing the connection of the elements and devices and the disconnection of the elements and the means for preventing movement thereof.

42. In a registering mechanism, the combination with a plurality of movable elements, of transfer devices therefor, actuators for said devices normally connected thereto, means for disconnecting the devices and actuators, and means controlled by the movable elements of the registering mechanism for connecting the devices and actuators so that the latter may move the former to effect the transfer.

43. In a registering mechanism, the combination with a plurality of movable elements, of transfer devices therefor normally disconnected therefrom, actuators for said devices normally connected thereto, means for connecting the elements and transfer devices and disconnecting said devices and their actuators, and means controlled by the elements for connecting the devices and actuators so that the latter may move the former to effect the transfer.

44. In a registering mechanism, the combination with a plurality of movable elements, of transfer devices therefor, actuators for said devices normally connected thereto, means for disconnecting the devices and ac-

tuators, and trip pawls actuated by the movable elements for connecting the devices and actuators so that the latter may move the former to effect the transfer.

45. In a registering mechanism, the combination with a plurality of movable elements, of transfer devices therefor, actuators for said devices, slides normally connecting the elements and devices, means for moving the transfer devices to connect them to the movable elements and disconnect them from the actuators, and means controlled by the elements for moving the slides to connect the elements and actuators so that the transfer may be effected.

46. In a registering mechanism, the combination with a plurality of movable elements, of transfer devices therefor, actuators for said devices normally connected thereto, means for connecting the movable elements and transfer devices and disconnecting the said devices and actuators, and means positively preventing movement of the transfer devices while they are connected to the elements and disconnected from the actuators.

47. In a registering mechanism, the combination with a plurality of movable elements, of transfer devices therefor, actuators for said devices normally connected thereto, means for connecting the movable elements and transfer devices, and disconnecting the said devices and actuators, means positively preventing movement of the transfer devices while they are connected to the elements and disconnected from the actuators, and means controlled by the movable elements for withdrawing the preventing means and connecting the transfer devices and actuators so that the transfer may be effected.

48. In a registering mechanism, the combination with a plurality of movable elements, of transfer devices therefor, actuators for said devices normally connected thereto, means for connecting the movable elements and transfer devices and disconnecting the said devices and actuators, means positively preventing movement of the transfer devices while they are connected to the movable elements and disconnected from the actuators, and means connected to the elements for withdrawing the preventing means, the latter means in turn connecting the transfer devices and actuators so that the transfer may be effected.

49. In a registering mechanism, the combination with a plurality of movable elements, of transfer devices therefor, actuators for said devices normally connected thereto, means for disconnecting the transfer devices and actuators, means operated by the movable elements for connecting the devices and the actuators so that the latter may move the former to effect the transfer,

and mechanism normally locking the connecting means, the said locking mechanism being constructed to be withdrawn as the movable elements move from "nine" to "zero" to enable said elements to operate the connecting means.

50. In a registering mechanism, the combination with a plurality of movable elements, of transfer devices therefor, actuators for said devices normally connected thereto, means for disconnecting the transfer devices and actuators, trip pawls operated by the movable elements for connecting the devices and the actuators so that the latter may move the former to effect the transfer, and mechanism normally locking the trip pawls, the said locking mechanism being constructed to be withdrawn as the movable elements move from "nine" to "zero" to enable said elements to operate the trip pawls.

51. In a registering mechanism, the combination with a plurality of movable elements each bearing the digits, of means for operating the elements to expose the digits of each element singly, transfer devices, including trip pawls, for said elements, and means for positively locking said trip pawls in all positions but one of said elements.

52. In a registering mechanism, the combination with a plurality of movable elements each bearing the digits, of means for operating the elements to expose the digits of each element singly, transfer devices for said elements, trip pawls controlled by the elements for establishing an operative relation between said elements and transfer devices, and means positively preventing movement of said pawls during the operation of the elements except when said elements are operated to expose their zeros.

53. In a registering mechanism, the combination with a plurality of movable elements each bearing the digits, of means for operating the elements to expose the digits of each element singly, transfer devices for said elements, trip pawls actuated by the elements for establishing an operative relation between said elements and transfer devices, means preventing movement of said pawls during the operation of the elements except when the zeros of said elements are exposed, and means for restoring the said pawls to their normal position after being operated by the elements.

54. In a registering mechanism, the combination with a plurality of movable elements each bearing the digits, of means for operating the elements to expose the digits of each element singly, transfer devices for said elements, actuators for said devices and disconnecting said devices and actuators, trip pawls actuated by the elements for again connecting the devices and actuators, means locking said pawls during the opera-

- tion of the elements except when the zeros of said elements are exposed, and means for restoring the said pawls to their normal position after being operated by the elements.
- 5 55. In a registering mechanism, the combination of a plurality of registering elements, operating and transferring mechanisms therefor, means for operatively disconnecting the registering elements and the 10 operating and transferring mechanisms, means positively locking said elements when out of the control of said mechanisms and means for withdrawing the locking means when said elements are under the control of 15 said mechanisms.
56. In a registering mechanism, the combination of a plurality of registering elements, operating and transferring mechanisms therefor, means for operatively disconnecting the registering elements and the 20 operating and transferring mechanisms, a shaft and a plurality of pawls fast thereon for positively locking said registering elements when out of the control of said mechanisms, and means for rocking said shaft simultaneously to withdraw said pawls from locking positions when said elements are under the control of said mechanisms.
57. In a registering mechanism, the combination with a plurality of registering elements, of operating and transferring mechanisms therefor, devices for locking said registering elements when out of the control of either of said mechanisms, and means for 35 positively moving said devices into locking position and also for simultaneously withdrawing all of said locking devices from locking position when said elements are under the control of said mechanisms.
- 40 58. In a registering mechanism, the combination with a plurality of movable elements, of operating, transferring, and resetting mechanisms therefor, means locking said elements when out of the control of any 45 of said mechanisms, and means for positively moving said locking means into locking position and also for withdrawing simultaneously all of said locking means when 50 said elements are under the control of any of said mechanisms.
59. In a registering machine, the combination with a registering device, of actuators therefor, manipulative means for moving said actuators, means for positively returning said actuators and said manipulative 55 means to normal position, and an auxiliary device for assisting the final increment of movement for the purpose specified.
60. In a registering machine, the combination with a registering device, of actuators therefor, manipulative means for positively moving said actuators, means for positively returning said manipulative means to normal position, and an auxiliary device for positively assisting the final increment of 65 movement for the purpose specified.
61. In a registering machine, the combination with registering wheels, of disks carried by said wheels and having notches formed therein, transfer elements for said 70 registering wheels, trip levers therefor, arms normally locking the trip levers in untripped position by engagement of said arms with said disks and adapted to permit the tripping of said trip levers only when the notches are brought into operative relationship with said arms, and means for actuating said transfer elements whose levers have been tripped.
- 75 62. In a registering machine, the combination with registering wheels, of transfer elements for said registering wheels, trip levers for preparing said transfer elements to effect transfers, levers for positively locking said trip levers against movement in 80 tripped and untripped positions through engagement of the levers with the disk and adapted to be rotated when said notches are in operative relationship with said levers to 85 permit movement of said trip levers to untripped position, and means for bodily moving said locking levers normally to lock said trip levers in untripped position.

In testimony whereof I affix my signature in the presence of two witnesses.

THOMAS CARROLL.
